(57) CLAIM

We claim the ornamental design for a digital music player, as shown and described.

DESCRIPTION

FIG. 1 is a front perspective view of a digital music player showing my new design;

FIG. 2 is a front view of the digital music player;

FIG. 3 is a rear view of the digital music player;

FIG. 4 is a left side view of the digital music player;

FIG. 5 is a right side view of the digital music player;

FIG. 6 is a top view thereof; and,

FIG. 7 is a bottom view thereof.

The broken lines are for illustrative purpose and form no part of the claimed design.
